UNITED STATES PATENT OFFICE

WALTER J. GADSBY, OF BOSTON, MASSACHUSETTS, ASSIGNOR TO ROXBURY CARPET COMPANY, OF SAME PLACE.

DESIGN FOR CARPET.

SPECIFICATION forming part of Design No. 11,983, dated October 26, 1880.

Application filed August 13, 1880. Term of patent 3½ years.

To all whom it may concern:

Be it known that I, WALTER J. GADSBY, of Boston, in the county of Suffolk and State of Massachusetts, have invented a new and original Design for Carpets, of which the following is a specification.

The nature of my design is shown by the accompanying photographic illustration, forming a part of this specification.

10 The design is composed of a chintz-work of leaves and flowers on curved stems or branches, substantially as shown in the accompanying photographic illustration, the blossoms being of various forms and sizes. The design is,

however, too intricate to admit of concise description. 15

I claim—

The design for a carpet, substantially as shown in the accompanying photographic illustration. 20

In testimony whereof I have signed my name to this specification, in the presence of two subscribing witnesses, this 3d day of August, A. D. 1880.

WALTER J. GADSBY.

Witnesses:

W. F. SIMPSON,

GEO. W. GRANWARD.
